2 Claims**ABSTRACT OF THE DISCLOSURE**

A rudder system is provided wherein the rudder is comprised of an upper and lower section each of which may be operated individually or in concert with each other.

BACKGROUND OF THE INVENTION

This invention relates to a rudder system and more particularly to a dual rudder having two distinct sections which may be employed either individually or in concert so as to provide the necessary control without inhibiting the speed of a craft. The invention may be used on any ship or vessel but it is primarily intended for use in connection with sailboats.

The rudder area needed to control a sailboat varies according to the maneuver being performed. For instance, when steering to windward only a small rudder is required to control the boat but when steering on hard reaches or tacking, a rudder having a considerably greater area is necessary in order to effect the desired turns.

Heretofore, sailboats have been provided with Rudders which could not adjust to the varying needs of the boat. As a result, a full rudder would be unnecessarily employed when steering to windward, etc. and speed lost because of the rudder's drag against the slip-stream of the boat. Rudders having two sections are known but both sections invariably act in concert so that their effect on the boat is essentially the same as that of a one piece rudder.

SUMMARY OF THE INVENTION

The present invention resolves these problems by means of a rudder consisting essentially of upper and lower sections which may be operated individually or in concert. The upper or trim section of the rudder preferably has an area somewhat smaller than the lower section so that the least amount of drag will be encountered during those times when a full rudder is not necessary. The area of both sections of the rudder will be determined to some extent by the size of the boat to which it is attached.

BRIEF DESCRIPTION OF THE DRAWINGS

FIG. 1 shows a sketch, partly in section, of the dual rudder and operating mechanism of the invention.

FIG. 2 is an elevational cross-section view of the bolt locking mechanism shown in FIG. 1 which permits both upper and lower sections of the rudder to act in concert.

FIG. 3 is a top plan view of the bolt locking mechanism shown in FIG. 2 along lines 3—3.

DETAILED DESCRIPTION OF THE DRAWINGS

FIG. 1 shows a rudder, generally designated 1, mounted on the skeg portion 2 of the sailboat. The rudder is shown as comprising two parts; an upper or trim section 3 and a lower or main section 4. Each of these sections is adapted so that they may act individually or in concert. The main rudder section 4 has an area approximately twice that of the trim section 3. The main section is fixedly secured to a main steering post 5 which is adapted for pivotal movement around a vertical axis. Preferably, the main post 5 will have its lower end pivotally mounted in a bracket 6 extending from the skeg 2 of the boat. The main post 5 extends through the horn timbers 7 of

2

the boat. A sprocket wheel 8 is fixedly attached to its upper end and keyed to sprocket wheels 9 and 10 by a continuous drive chain 11. Sprocket 10 is fixedly positioned on the distal end of steering column 12 on which main steering wheel 13 is mounted. Sprocket wheel 9 may be fixed in position by any suitable means, such as a cross-axle.

When the main steering wheel is moved the main rudder section is activated by means of the drive chain and sprocket system.

The upper or trim section 14 is fixedly secured to a shaft 15 which is rotatably mounted in a sleeve-like relationship to the main post 5. Bushings 16 are provided in the opening in the horn timber so as to establish bearings by which the shaft 15 is journaled for rotation on and about the axis of the post 5. The bushings are oppositely shouldered as shown to secure against axial displacement. A sprocket wheel 17 is mounted on the shaft 15 in perpendicular relationship and connected with sprocket wheels 18 and 19 by a continuous drive chain 20. Sprocket 19 is perpendicularly attached to the distal end of steering post 21 which projects from and is rotatably mounted in steering column 12. A trim steering wheel 22 is provided as shown, connected to the end steering post 21 so that when turned it will cause activation of the trim section of the rudder by means of the chain drive and sprocket system.

When performing certain maneuvers with the boat, such as tacking, etc. it will be necessary to employ the full rudder rather than merely using the trim section alone. In those instances, the rudder sections 3 and 4 will be locked together by a locking means generally designated 22. The locking means is more clearly illustrated in FIGS. 2 and 3.

35 In FIG. 2, a handle 23 is shown positioned in the bottom portion of a binnacle 24. The handle is attached to a cable 25 which rides on pulleys 26 and 27 and connects with the upper arm of a bell crank 28. The pulleys 26 and 27 are attached to the structure of the boat by support means 29 and 30, respectively. The bell crank 28 is secured to the structure by support means 31 and is pivotably mounted thereon by a stud 32. The lower end of the bell crank has a yoke configuration 33 which is keyed to the flange portion of a floating collar 34. The floating collar is slideably mounted on the distal end of main steering post 5. The flange portion of floating collar 34, which is opposite the yoke engaged portion, is fitted in a slot 35 in the head portion 36 of a pin 37. The pin is biased by a spring 38 which is mounted on a flange 39 formed at the middle of the pin and constrained by the top 40 of a housing unit 41. The bottom portion of the pin, which is shown in the locked position, is slideably disposed in passageway 42 which extends through sprocket wheel 8 into a hole 43 in sprocket wheel 17.

55 When the handle 23 is pulled the bell crank 28 pivots on stud 32 and causes the floating collar 34 to slide up on main steering post 5. This upward action causes the distal end of the pin 37 to be moved away from its seat in hole 43 and permits individual operation of the rudder sections. When disengaged from hole 43 the pin 37 will ride on the top of sprocket wheel 17. Alternatively, a catch may be provided to which the handle 23 may be hooked so as to insure that the pin 37 will remain retracted from the hole 43. When the rudder sections are aligned and, where applicable, the handle is disengaged from its catch, the pin 37 will move downward into the hole 43 under the action of the spring 38. The two sections of the rudder will then be locked together and will act in concert. FIG. 3 shows a top plan view of FIG. 2. The drawing more clearly illustrates the disposition of the locking pin 37 on sprocket wheel 8.

The flexibility offered by the present invention makes it ideal for use on sailboats intended for racing. In cases where speed is important the unnecessary use of a full rudder, and resulting loss of speed, when steering to windward, etc. is avoided by the individual use of the 5 trim rudder.

While the rudder installation has been shown and described in detail, it is obvious that this invention is not to be considered as being limited to the exact form disclosed, and that changes in detail and construction may 10 be made therein within the scope of what is claimed without departing from the spirit of this invention.

What is claimed is:

1. A rudder assembly comprising
  - (a) a main rudder section,
  - (b) first mounting means for said main section, said 15 mounting means being adapted so as to rotate about a vertical axis,
  - (c) a trim rudder section in an upper position relative to said main section,

20

- (d) second mounting means for said trim section, said second mounting means, being adapted so as to rotate around the vertical axis of said first mounting means,
- (e) steering means for said main and trim sections permitting individual operation of said sections, and,
- (f) locking means adapted so as to lock said main and trim sections together substantially in alignment and permit their concerted action.

2. A rudder assembly as defined in claim 1 wherein the area of said main rudder is twice the area of said trim section.
